UNITED STATES PATENT OFFICE.

THOMAS E. CLARKE, OF SAN GABRIEL, CALIFORNIA.

MAIL-BOX STAND AND SHELTER.

1,101,905.

Specification of Letters Patent.

Patented June 30, 1914.

Application filed September 2, 1913. Serial No. 737,672.

To all whom it may concern:

Be it known that I, THOMAS E. CLARKE, a citizen of the United States, and resident of San Gabriel, county of Los Angeles, and State of California, have invented a new and useful Mail-Box Stand and Shelter, of which the following is a specification.

My invention relates to the construction 10 of a stand and shelter adapted to support and shelter individual mail boxes along mail delivery routes and also pieces of mail matter too large to be placed in individual mail boxes.

Residents along the many rural free delivery routes are required to provide receptacles for their mail matter and to place them where they are readily accessible to the carrier. This has resulted in the placing 20 of unsightly groups of mail boxes at cross-roads and at many other points along the various mail routes. These individual mail boxes are usually supported on separate posts and no suitable shelter is provided 25 for mail which cannot be placed in the boxes.

The object of this invention is to provide a stand having a shelf of sufficient length to accommodate all of the private 30 mail boxes in each of said groups and also to provide shelf room and shelter for parcels too large to be placed in said boxes. By assembling the boxes of each group in one place the work of the carrier is simplified and facilitated. These mail box stands are generally conspicuously located on well traveled highways and obviously a sign, either for advertising or containing information, displayed in connection with the 35 stands will receive considerable notice, therefore the brace connecting the upper ends of the standards supporting the device has been so designed as to provide a limited sign space. This member while giving to 40 the stand the necessary stability also adds greatly to the value of the device. The construction by means of which these and other beneficial results are attained is fully described herein and is illustrated in the accompanying drawings in which:

Figure 1 is a front elevation of the com-

plete device. Fig. 2 is a vertical section taken on the dotted line $a-a$ in Fig. 1, and Fig. 3 is a horizontal section taken at $b-b$ in Fig. 2.

55

Throughout the several views like characters indicate like parts and referring to the details of construction 5 indicates uprights or standards which support the device. Each standard consists of two angle 60 irons riveted or bolted together. The angle irons are split near their lower ends and half of each turned out at a right angle forming shoulders 5^a which resting upon the ground support the stand while the other 65 halves 5^b embedded in the ground hold the device upright.

The upper ends of the standards are securely held together and parallel to each other by a rectangular plate 6. This plate 70 is secured between the upper ends of the angle irons forming the standards 5 by means of four or more rivets which pass through the ends of the plate and through the angle irons. This plate 6 provides ample 75 space for sign purposes and may be so used if desired.

7 is a narrow brace passing from standard to standard.

8 is a roof supported by brackets 9 which 80 are riveted to the standards 5.

10 is a shell consisting of two or more slats which extend between the brackets 9.

11 is a mail box of which any required number may be provided. The boxes may 85 be loosely placed upon the shelf or may be secured by bolts, screws or other fasteners to the shelf. The space between the mail boxes and on top of them provides ample space for parcels and in a position 90 where they are sheltered by the roof.

The simple, inexpensive and durable form of construction shown is an important feature of the invention and likewise the design of the bracing consisting principally 95 of a plate 6 which also serves as a sign and has considerable commercial value if so utilized.

Having thus described my invention what I claim as new and desire to secure by Letters Patent is:

In a mail box stand and shelter, the com-

combination of standards each consisting of angle irons bolted together; a plate extending between the upper ends of said standards and securely riveted to each; brackets attached to said standards beneath said plate; a roof supported by said brackets; and a shelf beneath said roof also supported

by said brackets; all substantially as described and for the uses and purposes set forth.

THOMAS E. CLARKE.
